(57) **CLAIM**

The ornamental design for an atomizer mask for inhaler, as shown and described.

DESCRIPTION

FIG. 1 is a front, top, and right side perspective view of an atomizer mask for inhaler, showing our new design; FIG. 2 is a rear, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines in the figures illustrate portions of the atomizer mask for inhaler that form no part of the claimed design.
